(57) **CLAIM**

The ornamental design for a bait fish fishing rod, as shown and described.

DESCRIPTION

FIG. 1 is a side elevational view of the bait fish fishing rod having a reel and line depicted;

FIG. 2 is a top view the bait fish fishing rod;

FIG. 3 is a bottom view thereof;

FIG. 4 is an enlarged end view thereof;

FIG. 5 is an enlarged tip view thereof; and,

FIG. 6 is a partial view of FIG. 1 depicting the grip sections and line entry.

The broken line showing of environment in FIG. 1 is for illustrative purposes only and forms no part of the claimed design.
